Application August 29, 1949, Serial No. 112,918

7 Claims. (Cl. 34—58)

1

This invention relates to improvements in centrifuges adapted to apply centrifugal force to discrete lots of materials.

In many industrial processes it is desirable to centrifuge materials in discrete lots to effect separation of components. This is usually carried out by supporting a number of discrete lots of materials in suitable containers around the circumference of a circle, rotating the resulting assembly around the center of the circle at slowly increasing speed for a definite time, rotating at maximum speed, and then gradually reducing the speed of the assembly until it is brought to rest. The resulting lots of centrifuged materials are then removed, are replaced by lots of uncentrifuged materials, and the process is repeated. This is essentially a batch-type operation. When it is desired to combine the centrifuging of discrete lots of materials with other steps to produce a continuous-type process, difficulties are caused by bunching or improper spacing of lots of materials at one point in the process.

Among others, the frozen-food industry offers a number of examples of such processes. It is frequently desirable to remove excess water from packages or lots of food by centrifuging prior to freezing, and to pass the centrifuged lots or packages in regularly spaced sequence into and through a freezing zone. Since conventional centrifuges deliver a number of lots or packages at one time, these become bunched, and some means of separating them into a regularly spaced sequence must be provided.

In processes where it is desired to separate materials into layers by centrifuging, it is also important that a centrifuged package or lot of materials be brought to rest very gradually in order to avoid stirring up and again mixing the resulting layers. When centrifuged lots are to be subsequently treated by continuous processes, some means of regularly spacing them must be provided.

It would be very desirable to have a centrifuge which, while running continuously, would deliver centrifuged lots of materials at regularly spaced intervals of time, and which would apply gradually increasing centrifugal force of such lots of materials until a maximum is reached and would gradually reduce centrifugal force until the materials are brought substantially to rest.

It is an object of this invention to provide a centrifuge which may deliver discrete lots of centrifuged materials at regularly spaced intervals of time while in continuous operation.

Another object is to provide such a centrifuge

2

in which each individual lot of materials may be subjected to centrifugal force, gradually increasing in intensity to a maximum value, and subsequently gradually decreasing to substantially zero.

Other objects and advantages will become apparent as this disclosure proceeds.

I have found that these objects may be attained in a centrifuge provided with a planetary head system. Such head system comprises a central power-driven shaft; a cross member attached to and carried by the central shaft adjacent to an end thereof; mechanical means for continuously, alternately, and gradually moving a plurality of containers for discrete lots of materials in balanced relationship from a dead center in line with the longitudinal axis of said central shaft to a maximum distance from said dead center position and back to said dead center position, said mechanical means comprising speed-reducing gearing driven by power from said central shaft and a plurality of container-carrying members, movable in closed paths around centers of rotation spaced equidistant from said central shaft and passing through the extended longitudinal axis of said central shaft, actuated by said speed-reducing gearing and movably carried by said cross member.

The attached drawings illustrate diagrammatically one of the several possible types of construction which embody this invention. Figure 1 is a plan of one type of apparatus which I have found to be particularly efficient in the frozen-food industry, and Figure 2 is a vertical section through the apparatus of Figure 1 on the line 2—2 but drawn on larger scale. Like reference numerals indicate like parts in both figures.

With reference thereto, the numeral 5 indicates a central rotatably mounted shaft which, in this particular modification, is made hollow. Shaft 5 is mounted in bearing 31 supported by beams 30. A motor 6 and belt 7 are provided to drive shaft 5. A cross member 8 is firmly attached to and is carried by shaft 5, and for the purpose of reducing weight may be constructed as an open rigid framework as shown. Spindles 9, 9 are carried by member 8 in sockets 10, 10. Spindles 9 are disposed equidistant from each other in a consecutive series around the circumference of a circle having its center at the extended longitudinal axis of shaft 5, for the purpose of obtaining a balanced relationship.

Upon each of spindles 9 a head member 13 is rotatably mounted. Members 13 are preferably formed as an open framework, as shown, since

this type of construction furnishes the necessary strength in combination with low weight. At each corner of head member 13 an annular member 14 is rigidly attached. Within each of members 14 a member 15 adapted to detachably hold lots or packages 16 of material to be centrifuged is rotatably mounted. Member 15 is constructed to fit within an annular portion of member 14 as a rotatable shaft fits within its bearing. Member 15 may be constructed, as shown, from two thin plates of metal or other suitable material disposed above and below member 14, held together by bolts or rivets and provided with projecting lips which slide freely upon member 14. When this type of construction is used each of members 15 must be provided with an opening of such size and shape as to fit packages 16 tightly. In combination, members 14 and 15 form a mechanical means for detachably and rotatably holding packages 16.

Head members 13 and members 14 and 15 must be of such size and so disposed that packages 16 are held equidistant from each other in consecutive series around the circumferences of circles having their centers at the center of the corresponding spindles, having radii equal to the perpendicular distance between the centers of the spindles and the longitudinal axis of the central shaft 5, and lying in a plane spaced outward from the end of shaft 5 adjacent to the point of attachment of cross member 8.

A means for actuating reducing gearing is shown as stationary ring gear 17 surrounding shaft 5 and supported by the housing 20. Ring gear 17 may be made integral with housing 20, welded thereto as shown by spot welds 32, or any other suitable means for attachment may be used. Assemblies of reducing gearing and shafting 18 are attached to and carried by cross members 8 and are disposed to be driven by meshed contact with ring gear 17, and to drive gears 19 rigidly attached to head members 13. Non-interfering and balanced relationship between the head members 13 and members 14 is secured and maintained by positioning gears 19 in mesh with corresponding gears of assemblies 18, and by positioning the latter in mesh with gear 17.

In operation for removing excess liquids from solids, porous or perforated containers 16 filled with materials to be centrifuged are forced into openings in members 15 and are held there by friction. Motor 6 is then started and shaft 5 rotates, carrying cross member 8 with it. Since ring gear 17 is held stationary by housing 20, assemblies 18 are driven and in turn drive gears 19, thus causing head members 13, to revolve slowly about spindles 9. As rotation continues, each container will in turn occupy a dead center position in line with the central axis of shaft 5. From this dead-center position each container will in turn be continuously and gradually moved outward by the rotation of the corresponding head member 13 to a maximum distance and slowly returned to dead center. As each returns to dead center an operator may arrest its rotation around the center of shaft 5 by suitably applying some form of brake to member 15, since member 15 is rotatable within member 14. This brake will ordinarily be merely the hand of the operator or may be any of the familiar types of mechanical, magnetic, or air actuated brakes which it may be desired to use. A fresh package of material to be centrifuged is then placed upon the package which

has been centrifuged and a downward pressure is exerted on it, thus forcing the centrifuged package on through member 15 and leaving a new package in its place. It is not necessary to arrest the motion of members 14 and 15 around the axis of spindles 9 since this motion is very slow, one revolution about spindles 9 occurring in the entire time required for centrifuging each package 16. The time required is dependent upon the type of material and package being centrifuged and may often be in the range from 2 to 8 minutes, but may also be either below or above this range. The builder will choose assemblies of reducing gearing to fit the time of rotation about spindles 9 to the requirements of the particular materials to be centrifuged. The centrifuged package then falls through the central opening of hollow shaft 5 and may be caught upon a moving belt or conveyor if desired. The centrifuge thus delivers discrete lots of centrifuged materials singly and at regular intervals of time.

Many modifications in the apparatus and procedure described above will at once suggest themselves as equivalents of details described. For instance, it is obvious that shaft 5 may be made solid, provided that the containers are lifted from member 15 instead of being pushed through it. Many equivalents of the motor and belt drive are known, such as a motor mounted directly upon the shaft, a motor connected to the shaft by gears, chain belt, or other means. Cross member 8, instead of the open framework shown, may be a triangle, disc, "spider," or other desired shape. The number of spindles carried by the cross member may be increased to 3, 4, or more, if desired. The spindles themselves may be any equivalent device for rotatably carrying one member upon another.

Head members 13 may be of any shape desired, and it is not intended to exclude the use of equivalent belts or conveyors actuated by an equivalent of reducing gear assembly 18 and moving in closed paths upon tracks which are stationary with relation to the corresponding cross members 8. Members 15 may be ordinary centrifuge buckets, and member 14 may be arranged to swing upon a trunnion if desired.

It thus will be seen that the centrifuge of my invention may be constructed in many modifications without departing from its spirit and scope which are limited only by the subtended claims.

Having described my invention and explained its operation, I claim:

1. A centrifuge comprising in combination a central power-driven shaft; a cross member attached to and carried by said central shaft adjacent to an end thereof; a plurality of spindles attached to and carried by said cross member, singly disposed equidistant from each other in a consecutive series around the circumference of a circle having its center at the longitudinal axis of said central shaft; a plurality of head members, singly disposed upon and rotatably carried by each of said spindles; a plurality of containers adapted to hold materials to be centrifuged; mechanical means, attached to and carried by each of said head members, for detachably holding the plurality of said containers singly disposed equidistant from each other in a consecutive series around the circumference of a circle having its center at the center of the corresponding spindle, having a radius equal to the perpendicular distance between the center 70 of said spindle and the longitudinal axis of said

central shaft, and lying in a plane spaced outward from the end of said central shaft adjacent to said cross member; and mechanical means, driven by power from said central shaft, for rotating said head members around their corresponding spindles in non-interfering relationship with each other at such speed that one revolution around said spindles occurs in the time required for centrifuging said materials.

2. A centrifuge comprising in combination a central power-driven shaft; a cross member attached to and carried by said central shaft adjacent to an end thereof; a plurality of spindles attached to and carried by said cross member, singly disposed equidistant from each other in a consecutive series around the circumference of a circle having its center at the longitudinal axis of said central shaft; a plurality of head members, singly disposed upon and rotatably carried by each of said spindles; a plurality of containers adapted to hold materials to be centrifuged; mechanical means, attached to and carried by each of said head members, for detachably holding the plurality of said containers singly disposed equidistant from each other in a consecutive series around the circumference of a circle having its center at the center of the corresponding spindle, having a radius equal to the perpendicular distance between the center of said spindle and the longitudinal axis of said central shaft, and lying in a plane spaced outward from the end of said central shaft adjacent to said cross member; and mechanical means, comprising speed-reduction gearing driven by power from said central shaft, for rotating said head members around their corresponding spindles in non-interfering relationship with each other at such speed that one revolution around said spindles occurs in the time required for centrifuging said materials.

3. A centrifuge comprising in combination a central power-driven hollow, vertical shaft; a cross member attached to and carried by said central shaft adjacent to an end thereof; a plurality of spindles attached to and carried by said cross member, singly disposed equidistant from each other in a consecutive series around the circumference of a circle having its center at the longitudinal axis of said central shaft; a plurality of head members, singly disposed upon and rotatably carried by each of said spindles; a plurality of containers adapted to hold materials to be centrifuged; mechanical means, attached to and carried by each of said head members, for detachably holding the plurality of said containers singly disposed equidistant from each other in a consecutive series around the circumference of a circle having its center at the center of the corresponding spindle, having a radius equal to the perpendicular distance between the center of said spindle and the longitudinal axis of said central shaft, and lying in a plane spaced outward from the end of said central shaft adjacent to said cross member; and mechanical means, comprising speed-reduction gearing driven by power from said central shaft, for rotating said head members around their corresponding spindles in non-interfering relationship with each other at such speed that one revolution around said spindles occurs in the time required for centrifuging said materials.

4. A centrifuge comprising in combination a central power-driven hollow, vertical shaft; a cross member attached to and carried by said central shaft adjacent to the upper end thereof;

a plurality of spindles attached to and carried by said cross member, singly disposed equidistant from each other in a consecutive series around the circumference of a circle having its center at the longitudinal axis of said central shaft; a plurality of head members, singly disposed upon and rotatably carried by each of said spindles; a plurality of containers adapted to hold materials to be centrifuged; mechanical means, attached to and carried by each of said head members, for detachably holding the plurality of said containers singly disposed equidistant from each other in a consecutive series around the circumference of a circle having its center at the center of the corresponding spindle, having a radius equal to the perpendicular distance between the center of said spindle and the longitudinal axis of said central shaft, and lying in a plane above the end of said central shaft adjacent to said cross member; and mechanical means, comprising speed-reduction gearing driven by power from said central shaft, for rotating said head members around their corresponding spindles in non-interfering relationship with each other at such speed that one revolution around said spindles occurs in the time required for centrifuging said materials.

5. A centrifuge comprising in combination a central power-driven shaft; a cross member attached to and carried by said central shaft adjacent to an end thereof; a plurality of spindles attached to and carried by said cross member, singly disposed equidistant from each other in a consecutive series around the circumference of a circle having its center at the longitudinal axis of said central shaft; a plurality of head members, singly disposed upon and rotatably carried by each of said spindles; a plurality of containers adapted to hold materials to be centrifuged; mechanical means, attached to and carried by each of said head members, for detachably and rotatably holding the plurality of said containers singly disposed equidistant from each other in a consecutive series around the circumference of a circle having its center at the center of the corresponding spindle, having a radius equal to the perpendicular distance between the center of said spindle and the longitudinal axis of said central shaft, and lying in a plane spaced outward from the end of said central shaft adjacent to said cross member; and mechanical means, driven by power from said central shaft, for rotating said head members around their corresponding spindles in non-interfering relationship with each other at such speed that one revolution around said spindles occurs in the time required for centrifuging said materials.

6. A centrifuge comprising in combination a central power-driven hollow, vertical shaft; a cross member attached to and carried by said central shaft adjacent to the upper end thereof; a plurality of spindles attached to and carried by said cross member, singly disposed equidistant from each other in a consecutive series around the circumference of a circle having its center at the longitudinal axis of said central shaft; a plurality of head members, singly disposed upon and rotatably carried by each of said spindles; a plurality of containers adapted to hold materials to be centrifuged; mechanical means, attached to and carried by each of said head members, for detachably and rotatably holding the plurality of said containers singly disposed equidistant from each other in a consecutive series around the circumference of a circle having its center at the longitudinal axis of said central shaft; a plurality of head members, singly disposed upon and rotatably carried by each of said spindles; a plurality of containers adapted to hold materials to be centrifuged; mechanical means, attached to and carried by each of said head members, for detachably and rotatably holding the plurality of said containers singly disposed equidistant from each other in a consecutive series around the circumference of a circle having its center at the longitudinal axis of said central shaft.

circle having its center at the center of the corresponding spindle, having a radius equal to the perpendicular distance between the center of said spindle and the longitudinal axis of said central shaft, and lying in a plane above the end of said central shaft adjacent to said cross member; and mechanical means, comprising speed-reduction gearing driven by power from said central shaft, for rotating said head members around their corresponding spindles in non-interfering relationship with each other at such speed that one revolution around said spindles occurs in the time required for centrifuging said materials.

7. A centrifuge comprising in combination a central power-driven hollow, vertical shaft; a cross member attached to and carried by said central shaft adjacent to the upper end thereof; two spindles attached to and carried by said cross member, singly disposed diametrically opposite each other in the circumference of a circle having its center at the longitudinal axis of said central shaft; two head members, singly disposed upon and rotatably carried by each of said spindles; a plurality of containers adapted to hold materials to be centrifuged; mechanical means, attached to and carried by each of said

10

20
25

head members, for detachably and rotatably holding the plurality of said containers singly disposed equidistant from each other in a consecutive series around the circumference of a circle having its center at the center of the corresponding spindle, having a radius equal to the perpendicular distance between the center of said spindle and the longitudinal axis of said central shaft, and lying in a plane above the end of said central shaft adjacent to said cross member; and mechanical means, comprising speed-reduction gearing driven by power from said central shaft, for rotating said head members around their corresponding spindles in non-interfering relationship with each other at such speed that one revolution around said spindles occurs in the time required for centrifuging said materials.
